UNITED STATES PATENT OFFICE

2,393,707

FURNACE WALL

Gustav A. Rehm, Worcester, Mass., assignor to
 Riley Stoker Corporation, Worcester, Mass., a
 corporation of Massachusetts

Application October 9, 1943, Serial No. 505,674

3 Claims. (Cl. 122—6)

This invention relates to furnace walls, and more particularly to walls of the water cooled type adapted for use with steam boiler furnaces.

One highly satisfactory prior construction for this purpose comprises a row of upright water tubes exposed on one side to the heat of the furnace and covered on the other side by a layer of refractory material, a layer of heat insulating material, and an outer casing of steel plates. However, this construction is expensive, since a considerable weight of steel is required, and much labor is involved in the manufacture and erection of the casing. Great care must be taken to ensure tight joints between the plates so that air leakage through the wall will be prevented.

It is accordingly one object of the invention to provide a comparatively inexpensive furnace wall construction which will require no steel plate casing and yet will be thoroughly effective in preventing air leakage into the furnace.

It is a further object of the invention to provide a furnace wall construction which can be erected in a simple and expeditious manner.

It is a further object of the invention to provide a furnace wall construction which will remain free from buckling and distortion resulting from changes in temperature.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts:

Fig. 1 is a vertical section through a furnace wall, the section being taken on the line of 1—1 of Fig. 2;

Fig. 2 is a section taken on the line 2—2 of Fig. 1;

Fig. 3 is a fragmentary elevation of the outside of the wall;

Fig. 4 is an enlarged fragmentary view showing the detailed construction of certain parts;

Fig. 5 is a vertical section through a modified wall construction, the section being taken on the line 5—5 of Fig. 6;

Fig. 6 is a section on the line 6—6 of Fig. 5; and

Fig. 7 is a fragmentary elevation of the outside of the wall.

The embodiment illustrated in Figs. 1 to 4 inclusive comprises a row of closely spaced vertical water tubes 10 which are connected at their lower ends to a horizontal header 11 and at their upper ends to a horizontal header 12. Steam releaser tubes 14 extend upwardly from the upper header 12. The end portions of the water tubes 10 are bent and staggered at their connections with the headers, and the spaces between these

bent portions are filled with refractory material 15 which may be applied in plastic form. These tubes 10 form the inner lining of a furnace wall, and they are exposed to the radiant heat of the furnace. In accordance with the usual practice, water is supplied continuously to the lower header 11 by suitable means (not shown) so that an upward circulation may be maintained through the tubes.

- 10 On the outer side of the row of water wall tubes 10 there is provided a layer of heat insulating material 17 which is preferably supported independently of the water tubes. In the particular embodiment illustrated this material 15 rests upon a horizontal shelf 18 which projects inwardly from a horizontal beam 19 located near the lower header 11. An upper horizontal beam 21 is located near the upper header 12, and these two beams 19 and 21 are connected by a series of 20 spaced vertically elongated upright buckstay members 22 of I cross section arranged with their central webs perpendicular to the plane of the wall and their inner flanges engaging the insulation 17. These buckstays 22 form a framework within which there is built a brick wall 24, this wall engaging the insulation 17 to provide lateral support therefor. The brick wall 24 is formed entirely of stretchers, laid in mortar with the joints staggered in the normal manner, the 30 thickness of the wall being equal to the width of the bricks. The lowermost course of bricks is laid in channel members 25 which are supported on the lower beam 19 with their flanges extending upwardly. The bricks extend between the flanges of the buckstay members 22, as best shown in Fig. 2, so that these members provide lateral support for the brickwork. Vertical ropes 26 (Fig. 4) of asbestos or the like may be installed between the brickwork and the central 40 webs of the buckstays to provide a seal against air leakage and at the same time allow for expansion of the brickwork.

Each vertical section of the brick wall 24 is preferably divided into panels by means of horizontal beams 28 of I cross section located in the plane of the wall, with the central webs of the beams horizontal and their flanges straddling the bricks to provide improved lateral support therefor. These beams 28 are free to "float" 45 vertically, their weight being carried solely by the brickwork. The ends of the beams are coped, as best shown in Fig. 4, to fit between the flanges of the buckstays 22 for free vertical sliding movement relative thereto.

50 In constructing this wall, the tubes and structural steel work will first be erected, whereupon the insulation and brickwork will be installed, starting at the bottom and working upwardly. As each panel of brickwork is completed, mortar 55 will be applied on the top of the upper course of

bricks, and one of the beams 28 will be placed on the mortar. Mortar will then be applied to the top of this beam, and the next course of bricks will be laid on this mortar. The brickwork may be constructed of any desired type of bricks, and need not be expensive. For example, ordinary red brick or a cheap grade of fire brick may be used, since the insulation will protect the bricks from high temperatures. The brickwork serves to provide lateral support for the insulation and to form a comparatively tight seal against the leakage of air into the furnace. The construction is such as to allow the brickwork to expand freely independently of the buckstays 22, so that the danger of cracking will be avoided.

In Figs. 5 to 7 inclusive there is shown a somewhat modified construction comprising a row of vertical water tubes 40 which are spaced apart more widely than the tubes 10 of Figs. 1 and 2. These tubes 40 are connected at their lower ends to a horizontal header 41 and at their upper ends to a horizontal header 42. Steam releaser tubes 44 extend upwardly from the upper header 42. Because of the wider spacing of these water wall tubes 40, there is no necessity for staggering their end portions, and they are accordingly connected to the headers in single lines. These tubes 40 form the inner lining of a furnace wall, and they are exposed to the radiant heat of the furnace. In accordance with the usual practice, water is supplied continuously to the lower header 41 by suitable means (not shown) so that an upward circulation may be maintained through the tubes.

The wide spacing of the water wall tubes 40 renders it inadvisable to apply insulating material directly to the outer side thereof, since such material is not well adapted to withstand exposure to high radiant heat and to slag deposits from burning fuel. Accordingly a layer of refractory material 46 is provided directly outside of the tubes, this layer preferably being constructed of shiplap firebrick tiles. These tiles rest upon a horizontal shelf 47 which projects inwardly from a horizontal beam 48 located near the lower chamber 41. Outside of the tiles 47 there is provided a layer of heat insulating material 50 which is likewise supported by the shelf 47. An upper horizontal beam 51 is located near the upper header 42, and this beam is connected to the lower beam 48 by a series of spaced vertically elongated upright buckstay members 52 of I cross section arranged with their central webs perpendicular to the plane of the wall and their inner flanges engaging the insulation 50. These buckstays 52 form a framework within which there is built a brick wall 54, this wall engaging the insulation 50 to provide lateral support therefor. The brick wall 54 is formed entirely of stretchers, laid in mortar with the joints staggered in the usual manner, the thickness of the wall being equal to the width of the bricks. The lowermost course of bricks is laid on the lower beam 48 and held in place laterally by angle bars 55 fastened to the beam. The bricks extend between the flanges of the buckstay members 52, as best shown in Fig. 6, so that these members provide lateral support for the brickwork. Vertical ropes 56 of asbestos or the like may be installed between the brickwork and the central webs of the buckstays to provide a seal against air leakage and at the same time allow for expansion of the brickwork.

Each vertical section of the brick wall 54 is preferably divided into panels by means of hori-

zontal beams 58 of I cross section located in the plane of the wall, with the central webs of the beams horizontal and their flanges straddling the bricks to provide improved lateral support therefor. These beams 58 are free to "float" vertically, their weight being carried solely by the brickwork. The ends of the beams are coped to fit between the flanges of the buckstays 52 for free vertical sliding movement relative thereto.

It will be noted that the wall of Figs. 5 to 7 is similar to that of Figs. 1 to 3 in all essential respects except for the wider spacing of the water wall tubes 40 and the addition of the firebrick tiles 46 between the tubes and the insulation. Both walls are comparatively inexpensive to construct, and adapted for long periods of satisfactory service under difficult operating conditions. No steel casing is required.

While the buckstay members 22—52 and the floating beams 28—58 have been described as of "I cross section," this wording when used in the claims is not to be given an unduly limited interpretation but is intended to include such equivalents as H beams having wider flanges than ordinary I beams, as well as members built up of channels, angles or the like to provide a substantially I or H cross section.

Having thus described my invention, what I claim as new and desire to secure by Letters Patent is:

1. A furnace wall comprising an inner row of water wall tubes, a layer of heat insulating material outside of the water tubes, a series of spaced vertically elongated upright buckstay members outside of the insulating material, brickwork located between the buckstay members and providing lateral support for the insulating material, and horizontal beams dividing the brickwork into panels, the buckstay members engaging the ends of the beams to support the same against movement outwardly of the wall, and the beams being slidably vertically relative to the buckstay members.

2. A furnace wall comprising an inner row of water wall tubes, a layer of heat insulating material outside of the water tubes, a series of spaced vertically elongated upright buckstay members outside of the insulating material, brickwork located between the buckstay members and providing lateral support for the insulating material, and horizontal beams of I cross section dividing the brickwork into panels, the beams being provided with horizontally positioned center webs and vertically extending flanges straddling the brickwork, and the ends of the beam being in vertical sliding engagement with the buckstays.

3. A furnace wall comprising an inner row of water wall tubes, a layer of heat insulating material outside of the water tubes, a series of spaced upright buckstay members of I cross section outside of the insulating material, the buckstay members having central webs perpendicular to the plane of the wall and laterally projecting flanges, brickwork located between the buckstay members to provide lateral support for the insulating material, the brickwork extending between the flanges of the buckstay members, and horizontal beams of I cross section dividing the brickwork into panels, the beams being provided with horizontally positioned central webs and vertically extending flanges straddling the brickwork, and the ends of the beams being coped to fit between the flanges of the buckstay members for vertical sliding movement relative thereto.

GUSTAV A. REHM.
